INVENTOR
H. R. Van Deventer.

UNITED STATES PATENT OFFICE.

HARRY R. VAN DEVENTER, OF SUMTER, SOUTH CAROLINA, ASSIGNOR TO SPLITDORF ELECTRICAL COMPANY, OF NEWARK, NEW JERSEY, A CORPORATION OF NEW JERSEY.

COMBINATION MAGNETO AND HORN.

1,249,255.

Specification of Letters Patent.

Patented Dec. 4, 1917.

Application filed March 20, 1916. Serial No. 85,414.

To all whom it may concern:

Be it known that I, HARRY RANDOLPH VAN DEVENTER, a citizen of the United States, residing at Sumter, in the county of Sumter 5 and State of South Carolina, have invented certain new and useful Improvements in Combination Magnetos and Horns, of which the following is a specification, reference being had to the accompanying drawing.

10 My invention relates to a combination dynamo and sound-producing device. Such dynamos, commonly known as magnetos, are commonly used on automobiles which also require a sound-producing or signaling device commonly termed a horn. Such horns are now sold as a unit complete in themselves, and in addition to the cost of the horn, it must be mounted on the automobile.

15 The object of my invention is to combine the horn with the magneto so that the means for actuating the magneto can be made at will to actuate the horn. A further object is to arrange the casing of the magneto so that it will support the horn mechanism and 20 form the casing therefor.

25 Other objects will be more fully pointed out hereinafter and covered by the appended claims.

In the accompanying drawing Figure 1 30 is an end view of a magneto embodying my invention, Fig. 2 a side view of same, and Fig. 3 an end view same as Fig. 1 with the casing removed. Like figures of reference denote the same parts wherever they are shown.

35 3 denotes a magneto of any suitable type, having an inclosing cover shown in section at 10. The shaft 2 of this magneto carries a gear 1.

40 Suitably supported on a stud shaft 6 is the gear 4 provided with an outwardly extending portion having teeth adapted to engage the projecting stud 5 of the horn diaphragm 11. As the construction of the parts 4, 5 and 11 is already well known, I will not 45 describe them in detail.

46 It will be noted that the diaphragm 11 is supported on an outwardly turned peripheral flange on the casing, and that bolted to this flange is the horn trumpet 12. This arrangement affords a cheap and efficient casing for 50 the horn mechanism.

Any suitable means may be employed for connecting the actuating gear 4 of the horn with the driving gear 1. The means shown

in Fig. 3, consists of the gear 7 mounted on 55 the lever 8 supported on the stud 9. The outer end 9* of this lever may be connected to a suitable rod or wire whereby it may be moved upwardly, thereby bringing gear 7 into engagement with gears 1 and 4 and 60 thereby actuating the horn. It is obvious that a friction device or any other suitable means can be employed to accomplish this result.

Having thus described my invention, I 65 claim:

1. In combination with a dynamo a sound-producing device carried thereby, means for actuating said dynamo, and means for actuating said sound-producing device adapted 70 to be brought into engagement at will with said dynamo actuating means.

2. In combination, a dynamo, a sound-producing device carried thereby, means for actuating said dynamo, means for actuating 75 said sound-producing device, and connecting means carried by said dynamo for driving said sound actuating means from said dynamo actuating means.

3. In combination, a dynamo having a rotating element, a dynamo framework supporting said rotating element, a diaphragm on said framework, means for vibrating said diaphragm, and means for connecting said diaphragm vibrating means with a rotating 80 part of said dynamo, substantially as described.

4. In combination with a dynamo, a sound-producing device carried on said dynamo and including a mechanically actuated 90 diaphragm horn and a casing inclosing and surrounding said dynamo and adapted to support the diaphragm of said horn, substantially as described.

5. In combination, a dynamo, a casing surrounding said dynamo and inclosing the working parts thereof, said casing having an annular flanged portion, a sound producing diaphragm mounted on said flanged portion, a shaft for the dynamo and means 100 driven by said shaft and inclosed by said casing and diaphragm whereby the latter may be actuated by the motion of said shaft.

In testimony whereof I hereunto affix my signature in the presence of a witness.

H. R. VAN DEVENTER.

Witness:

INEZ BETHELL.
